177,916

COMBINED LUMINAIRE AND BRACKET THEREFOR

Merle E. Keck, Bay Village, Ohio, and Edmund L. Izzi, Pittsburgh, Pa., assignors to Westinghouse Electric Corporation, East Pittsburgh, Pa., a corporation of Pennsylvania

Application October 26, 1955, Serial No. 38,578

Term of patent 14 years

(Cl. D48—31)

Figure 1 is a side elevational view of a combined luminaire and bracket therefor showing our new design; Fig. 2 is a front elevational view; and Fig. 3 is a top plan view.

The dominant features of our design are shown in the drawings by solid lines.

We claim:

The ornamental design for a combined luminaire and bracket therefor, as shown and described.
